(57) **CLAIM**

The ornamental design for a sheet junction, as shown and described.

DESCRIPTION

FIG. 1 is a front perspective view of a sheet junction showing our new design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a side view thereof; and,

FIG. 8 is another side view thereof.

The drawings include symbolic breaks. The portions between the break lines form no part of the claimed design. The boundary lines depict the bounds of the claim that forms no part of the claimed design.

1 Claim, 6 Drawing Sheets(56)
